OMNIDIRECTIONAL RADIO RANGE

David G. C. Luck, Hightstown, N. J., assignor to
 Radio Corporation of America, a corporation of
 Delaware

Application September 30, 1942, Serial No. 460,292

3 Claims. (Cl. 250—11)

1

This invention relates to omnidirectional radio ranges, and particularly to the provision of reference phase signals for such systems. One type of omnidirectional range is described in U. S. Patent No. 2,208,376 to D. G. C. Luck. A continuous wave carrier is radiated with a limacoid directive pattern. The directive pattern is continuously rotated, so that the signal picked up by a receiver is sinusoidally modulated at the pattern rotation frequency. The modulation phase depends on the direction of the receiver from the transmitter. It is necessary to provide a constant phase reference for comparison with the pattern rotation modulation at the receiver in order to provide azimuth indication. This has been done by impressing the reference signal on a subcarrier, or by distorting the reference signal to an impulsive shape, so that as the modulation peak occurs due north of the transmitter, for example, a brief impulse is radiated.

The principal object of the present invention is to provide an improved omnidirectional radio range with an improved reference phase transmission, in which the use of a subcarrier or of impulsive keying is avoided.

Another object is to provide an improved omnidirectional radio range system affording coarse and fine azimuth indications.

In accordance with this invention, the directive transmission is made by causing a field pattern to rotate at a uniform speed, while the reference transmission is made by modulating a non-directionally transmitted carrier at a frequency subharmonically related to the pattern rotation frequency. The non-directional carrier is of the same frequency as that used for the directional transmission. A fixed phasal relation is maintained at the transmitter between the pattern rotation and the non-directional modulation.

At the receiver the pattern rotation and reference modulations are separated by filters. The frequency of the reference modulation is multiplied to equal that of the directional modulation, and the relative phase of the two voltages indicated by a synchroscope, or the like.

Referring to the drawing, Fig. 1 is a schematic block diagram of a range transmitter according to the invention, and Fig. 2 is a similar diagram of a range receiver.

At the range transmitter, orthogonally related pairs of opposed antennas N, S and E, W are connected to the outputs of a pair of balanced modulators 1 and 3, respectively. A radio frequency oscillator 5 is connected through an amplifier 7

to the modulators 1 and 3 and to a power amplifier 9. The amplifier 9 is connected to a non-directional antenna 11.

An oscillator 13 is connected through a frequency divider 15 to the balanced modulator 1. The output of the frequency divider 15 is also connected through a 90° phase shifter 17 to the balanced modulator 3. A second frequency divider 19 is connected between the output of the frequency divider 15 and a combining circuit 21. A modulator 23 is arranged to modulate the power amplifier 9 under the control of the output of the combining circuit 21.

Fig. 2 is a schematic block diagram of a range receiver system according to the invention. A radio receiver 25 is connected to an antenna 27. The output of the receiver 25 is connected to filters 29, 31 and 33. The output of the filter 29 is connected directly to one of the usual orthogonally related deflection circuits of a cathode ray tube 35 and through a 90° phase shifter 37 to the other deflection circuit of the tube 35.

The output of the filter 33 is applied to a frequency multiplier 34, which is similarly connected to the orthogonal deflection circuits of a second cathode ray tube 39. A second 90° phase shifter 41 is provided for the tube 39. The cathode ray tubes 35 and 39 are provided with radial deflection electrodes. The radial deflection electrodes of the two tubes are connected together through an impulse shaper circuit 43 to the output of the filter 31.

The operation of the system is as follows: The oscillator 5 provides a carrier voltage which is amplified by the amplifier 7 and applied to the balanced modulators 1 and 3 and the power amplifier 9. The oscillator 13 provides a frequency of, for example, 720 cycles per second. The frequency divider 15 is adjusted for 12 to 1 frequency division, providing an output of 60 cycles per second. This voltage controls the balanced modulators 1 and 3, providing a rotating field of radiation from the antennas N, S, E and W, as described more fully in the aforementioned patent. The output of the amplifier 9 is radiated non-directionally by the antenna 11, modifying the figure-of-eight pattern of the antennas N, S, E and W to provide the limacoid pattern.

Reference phase modulation is impressed on the non-directional carrier by modulation of the power amplifier 9. The frequency divider 19 is arranged for 3 to 1 division, providing an output of 20 cycles per second for controlling the modulator 23. To provide fine indications of azimuth, as will appear more fully hereinafter, the output

of the oscillator 13, at 720 cycles per second, is added to the 20 cycle voltage in the combining network 21. Thus the non-directional carrier provides modulation at 20 cycles and at 720 cycles in constant phases, independent of direction, while the directional carrier is modulated at 60 cycles per second, the modulation phase being a function of direction.

The three modulation components are separated at the receiver station by the filters 29, 31 and 33. The 720 cycle component causes the cathode ray beam of the tube 35 to trace a circular path at the rate of 720 times per second. The 20 cycle component is converted to 60 cycles by the multiplier 34, causing the beam of the tube 39 to trace a circular path 60 times per second. The 60 cycle variable phase modulation component is converted by the impulse shaper 43 to a sharp pulse repeating at intervals of one-sixtieth second, coinciding with the peaks of the modulation from which it is derived. This pulse is applied to the radial deflection circuits of both cathode ray tubes 35 and 39, providing deflections 45 and 47 of the traces 49 and 51.

The coarse indicator tube 39 traces one circle for each pulse, while the fine indicator 35 traces 12 circles during the same period. The face of the tube 39 may be calibrated to indicate angles up to one-twelfth of a circle, or 30 degrees. Thus the tube 39 indicates the approximate bearing of the range transmitter as over 30° and less than 60°, and the tube 35 shows that the exact bearing is eleven and one-half degrees east of the first full thirty degrees. The exact bearing is thus 30 plus 11½, or 41½°.

Thus the invention has been described as an improved method of and means for providing reference phase transmission for omnidirectional radio ranges. A constant phase modulation at a subharmonic of the pattern rotation frequency is impressed on the non-directional carrier radiated by the "sense" antenna of the range transmitter array. The range receiver is provided with filters for separating the reference modulation from the pattern rotation modulation. The reference modulation is multiplied in frequency to provide a constant phase voltage equal in frequency to the variable phase directional modulation voltages. The two voltages are applied to a phase indicator calibrated to read azimuth.

I claim as my invention:

1. An omnidirectional radio range system including means for radiating a radio frequency carrier in a rotating directive field pattern and means for changing the shape of said pattern cyclically at frequencies harmonically related to the frequency of said pattern rotation whereby said carrier is modulated at one frequency with a phase depending upon azimuth and at other frequencies independent of azimuth, means for receiving and demodulating said carrier to produce a signal corresponding to the composite modulation thereof, filter means arranged to sep-

5 arate the components of said signal, means arranged to change the frequency of one of said components to a frequency equal to that of said pattern rotation, a phase responsive indicator device arranged to compare said latter component with the modulation derived from said pattern rotation to provide a coarse unique indication, and a second phase responsive indicator device arranged to compare said pattern rotation modulation component with a higher frequency component to provide a fine indication.

10 2. An omnidirectional radio range system, including means for radiating a carrier wave including two modulation components of constant azimuthal phase and means for radiating a suppressed carrier wave including a modulation component of phase depending upon azimuth, said three modulation components being of different and harmonically related frequencies; a receiver 15 including means for demodulating said carrier wave and means for separating said modulation components of different frequencies, means for changing the frequency of one of said constant phase components to a frequency equal to that of said component of variable azimuthal phase, means for comparing said frequency changed component with said variable phase component to provide a unique coarse indication of azimuth, and means for comparing the other of said constant phase components with said variable phase component to provide a fine indication of azimuth.

20 3. In an omnidirectional radio range, the method of providing azimuth information including 25 the steps of radiating a suppressed carrier wave with a modulation component of phase depending upon azimuth radiating a carrier wave with two modulation components of constant phases, said three modulation components being of different and harmonically related frequencies, receiving and demodulating said waves, separating 30 said modulation components of different frequencies, changing the frequency of one of said constant phase components to a frequency equal to that of said component of azimuthally dependent phase, comparing said frequency changed component with said constant phase component to provide a unique coarse indication of azimuth, and comparing the other of said constant 35 phase components with said component of azimuthally dependent phase to provide a fine indication of azimuth.
